UNITED STATES PATENT OFFICE

WILLIAM SCHMID, OF BRONSON, MICHIGAN, ASSIGNOR TO HARRY A. DOUGLAS, OF BRONSON, MICHIGAN

ELECTRIC SWITCH

Application filed August 8, 1930. Serial No. 473,872.

My invention relates to switches employing reciprocable handles and has for its general object the provision of a construction whereby the dimensions of such a switch may be reduced along its axis of movement. Hitherto guiding sleeves have been required for directing the movements of the reciprocable handles and these sleeves I am able to replace by an element of very short length, 10 measured along the axis of switch movement by means of the structure of my invention, whereby the switch structure is made very compact and is more adaptable to certain locations affording restricted room.

15 In accordance with my invention, I employ a guiding element having two angularly related branches, one of these branches having a hole therethrough through which the handle passes and which may be of small 20 dimension along the handle, so that the handle may be a correspondingly reduced length. The handle carries a contact actuator, this actuator and the other guide branch having interengaging formations positioned to 25 guide the handle and direct its movement together with the movement of the actuator thereon. The switch includes a spring contact that is desirably mounted apart from the actuator and which presses the actuator 30 toward the part that guides its movement. This spring is desirably a leaf spring, the actuator and spring having interengaging formations whereby the actuator and the handle are held in alternative positions in 35 which they are placed to open and close the switch. A casing is desirably employed for enclosing the switch, the actuator and the inner end of the handle, two contiguous angularly related walls of the casing constituting 40 a guiding element for the handle and actuator.

The invention will be more fully explained in connection with the accompanying drawing in which Fig. 1 is a view mainly in longitudinal section, parts being shown in elevation; Fig. 2 is a view at right angles to the direction at which Fig. 1 is taken, parts being shown in section and parts in elevation; Fig. 3 is a sectional view on line 3-3 of Fig. 45 1; and Fig. 4 is a perspective view illustrating

ing component parts of the structure in separated relation.

The casing illustrated preferably includes a generally cylindrical wall 1 and a second wall 2 which is angular to the first and constitutes therewith a switch receptacle of cup formation. The wall 1 is formed with prongs 3 which are passed through notches in the closure wall 4 and which are clinched into engagement with the outer flat face of said closure wall, whereby this wall and the cup part of the casing are held in assembly. The casing wall 4 desirably constitutes the contact carrier of the switch structure. The circuit wires 5 and 6 are illustrated, these wires being clamped within the larger portions of the metallic sleeves 7 and 8 respectively by means of binding screws 9 and 10. The reduced portions of these sleeves pass snugly through holes that are formed in the wall 4 and are riveted at their inner ends to form flanges 11 and 12 which clamp said wall against the larger portions of the sleeves. Metallic leaf springs 13 and 14 are penetrated by the reduced ends of the sleeves and are clamped against the wall 4 by the flanges 11 and 12 respectively. Said springs are formed with angular tails 15 and 16 that are received within recesses in the wall 4 to prevent these springs from being turned upon their mountings. The unmounted ends of the springs are brought together to close the circuit, by the means to be described, the resilience of the spring 13 being sufficient to separate it from the spring 14 when the circuit closing influence is removed. The cylindrical wall of the casing cup and the bottom wall 2 of such cup constitute two angularly related branches of a guiding element. The shank 17 on the handle 18 passes through an opening that is preferably formed at the center of the wall 2, the portion of this wall that margins said opening being desirably outwardly continued to pass through any suitable mounting such as the panel 19, this continuation of said wall being finally outwardly deflected to form a flange 20 that clamps the wall 2 against the mounting 19. The handle carries a contact actuator 21 upon its inner end. As the handle is preferably made of metal and as the contact 100

actuator desirably has direct engagement with the contact 13, such actuator is made of insulation, being clamped in place between the flange 22 upon the inner end of the handle and the shoulder 23 on the handle. Said contact actuator has a formation which is preferably a notch 24 in its periphery which takes part in guiding the movement of the handle and the actuator. The cylindrical wall of the 10 casing is formed with a rib 25 that extends in the direction of movement of the handle and which enters the notch 24 and cooperates with the contact actuator and the opening in the wall 2 to guide the handle and the actuator. 15 The unmounted end of the leaf spring 13 is engaged by a tongue 26. The unmounted end portion of the spring 13 desirably slopes to constitute a cam formation that cooperates with the actuator in effecting a depression of 20 the unmounted end of this spring against the unmounted end of the spring 14 when the handle is moved inwardly whereby the circuit is closed. When the handle is moved outwardly the spring 13, of its own resilience, will rise 25 to become separated from its engagement with the spring 14. The contact actuator and the leaf spring 13 are provided with interengaging formations whereby the spring serves to hold the actuator together with the handle 30 in the alternative switch adjusting positions to which these parts are placed. These interengaging formations are the aforesaid tongue 26 and the inclined unmounted end of the spring 13 which cooperate to hold the switch 35 in a circuit opening adjustment and the hump 27 over which the tongue 26 rides and which serves to hold this tongue and the actuator carrying it from forward movement when the switch is in a circuit closing adjustment. 40 Changes may be made without departing from the invention.

Having described my invention, I claim:

1. The combination with a guiding element having two angularly related branches; 45 of a handle passing through and reciprocable within a hole formed in one of said branches; and an electric switch having a contact actuator on said handle, said actuator and the other guide branch having interengaging 50 formations positioned to guide the handle and direct movement of said actuator angularly to the first mentioned guiding element branch, the actuator controlled contact being a leaf spring contact mounted apart from the 55 actuator and pressing said interengaging formations together.

2. The combination with a casing having two contiguous angularly related walls constituting a guiding element having two angularly related branches; of a handle passing through and reciprocable within a hole formed in one of said walls; and an electric switch in said casing having a contact actuator on said handle the handle and actuator 60 being loosely mounted in the casing, said

actuator and the other of said angularly related walls having interengaging formations positioned to guide the handle and direct movement of said actuator angularly to the first mentioned wall, the actuator controlled contact being a spring contact mounted apart from the actuator and pressing the same toward the second mentioned wall.

3. The combination with a casing having two contiguous angularly related walls constituting a guiding element having two angularly related branches; of a handle passing through and reciprocable within a hole formed in one of said walls; and an electric switch in said casing having a contact actuator on said handle, said actuator and the other of said angularly related walls having interengaging formations positioned to guide the handle and direct movement of said actuator angularly to the first mentioned wall, 70 the actuator controlled contact being a leaf spring contact mounted apart from the actuator and pressing the same toward the second mentioned wall.

4. The combination with a guiding element having two angularly related branches; of a handle passing through and reciprocable within a hole formed in one of said branches; and an electric switch having a contact actuator on said handle, said actuator and the other guide branch having interengaging formations positioned to guide the handle and direct movement of said actuator angularly to the first mentioned guiding element branch, the actuator controlled contact being a leaf spring contact mounted apart from the actuator and pressing the same toward the second mentioned guiding element branch, said actuator and leaf spring having interengaging formations whereby the actuator and the handle carrying it are held in alternative switch adjusting positions.

5. The combination with a casing having two contiguous angularly related walls constituting a guiding element having two angularly related branches; of a handle passing through and reciprocable within a hole formed in one of said walls; and an electric switch in said casing having a contact actuator on said handle, said actuator and the other of said angularly related walls having interengaging formations positioned to guide the handle and direct movement of said actuator angularly to the first mentioned wall, the actuator controlled contact being a leaf spring contact mounted apart from the actuator and pressing the same toward the second mentioned wall, said actuator and leaf spring having interengaging formations whereby the actuator and the handle carrying it are held in alternative switch adjusting positions.

In witness whereof, I hereunto subscribe my name.

WILLIAM SCHMID. 130
